UNITED STATES PATENT OFFICE

96,845

DESIGN FOR A COMBINED SHEAR AND CASTRATOR

Claude Marco, Stockton, Calif.

Application October 3, 1934, Serial No. 53,468

Term of patent 14 years

To all whom it may concern:

Be it known that I, Claude Marco, a citizen of the United States of America, residing at Stockton, in the county of San Joaquin and State of California, have invented a new, original, and ornamental Design for a Combined Shear and Castrator of which the following is a specification, reference being had to the accompanying drawing, forming a part thereof.

Figure 1 is a plan view of the combined shear and castrator, showing my new design,

Fig. 2 is an edge elevation of the design, and
Fig. 3 is an end view of the same.

I claim:—

The ornamental design for a combined shear and castrator substantially as shown.

CLAUDE MARCO.
